UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL RECEPTACLE.

Application filed March 10, 1920. Serial No. 364,785.

To all whom it may concern:

Be it known that I, REUBEN B. BENJAMIN, a citizen of the United States, residing at Chicago, in the county of Cook and State of Illinois, have invented new and useful Improvements in Electrical Receptacles, of which the following is a full, clear, concise, and exact description, reference being had to the accompanying drawing, forming a part 10 of this specification.

My invention relates to electrical receptacles and it has particular relation to receptacles comprising removably connected base and casing parts.

15 For a better understanding of my invention reference may be had to the accompanying drawings in which:

Fig. 1 is a vertical sectional view of an electrical receptacle embodying my invention, with portions thereof broken away for the sake of clearness;

Fig. 2 is a plan sectional view taken at the line 2—2 of Fig. 1;

Fig. 3 is a plan sectional view taken at the line 3—3 of Fig. 1;

Fig. 4 is a plan view of the electrical receptacle;

Fig. 5 is an elevational view of the upper portion of the receptacle, the closure and 30 maintaining member which cooperates with this portion of the receptacle, being removed;

Fig. 6 is a perspective view of the closure and maintaining element; and,

Fig. 7 is a perspective view of the insulating element which is normally associated with the portions shown in the Figs. 5 and 6.

In receptacles of the character hereinafter described it is essential that the base member, to which is attached the lamp socket proper, may be easily and quickly detached from the outer casing which serves as a protection therefor, the latter usually being of such character that a globe may be secured thereto. In the past, the disassembling of the two portions as just indicated, has been a feature more or less difficult of attainment without the use of various tools for separating the various portions of the receptacle.

50 It is an object of my invention, therefore, to provide a receptacle in which a base member is surrounded, and protected, by a metallic casing, and in which the casing and base member may be readily disassembled without the use of tools and other implements.

To this end I so arrange, and so form the base member and its associated casing that the two may be assembled and firmly secured together through the medium of certain novel openings and tongues registering therewith.

A further object of my invention is to provide a casing of the character above designated, in which one element only thereof, need be removed in order to render accessible the binding terminals.

Finally another object of my invention is to provide a simple and easily removable globe-supporting means, which is substantially integral with the above mentioned casing, 70 and which supports the globe without the interpositioning of screws or other fastening means.

As will hereinafter appear I attain the above objects by the provision of novel locking members which are associated with the casing and base member, and moreover, it will be apparent to those skilled in the art, that said objects are accomplished with the provision of the minimum number of parts, 80 and moreover, that the locking of the casing and base member is positive and accomplished with a minimum movement of the parts.

Referring now more particularly to the drawings, an insulating base 10 of porcelain, or other suitable insulating material, is of substantially cylindrical form, and is enclosed by a metallic casing 11, which has a downwardly extending portion forming a 90 husk 12, the latter being flared at its lower end and provided with an equitant portion 12a.

A globe 13 is shown as held in position by a member 14, having a portion 14a, 95 which is grasped by the equitant portion 12a of the husk 12, and a further supporting member 15, which is secured to the member 14, preferably by threaded engagement, as shown. It will be observed that by the last described combination, I provide an extremely simple and easily assembled globe-supporting structure which is substantially integral with the receptacle.

In order to lock the base 10 from rotating with respect to the casing 11, lugs 16 are formed integral with the casing 11 and are adapted to engage with bayonet joints, which comprise longitudinal recesses 17 formed on the outer surface of the base 10, 110

extending from the inner end thereof and having formed integral therewith transversely extending recesses 18. The arrangement is such that upon the insertion 5 of the base, the lugs 16 engage the longitudinal recesses 17, and serve to hold the base against relative rotation with respect to the casing. When the lugs 16 reach the end of the longitudinal recesses 17, they are 10 in position to engage the transverse recesses 18, this engagement being effected by rotation of the base 10, whereupon the latter and the casing 11 are locked and relative longitudinal movement therebetween is prevented. 15

Secured to the outer side of base 10 are conventional shell and center contacts 19 and 20 respectively, the former being threaded and enclosed in a suitable insulating sleeve or housing 21. Also secured to the base 10 are a pull switch mechanism 22, and wiring terminals 23 and 24 for the reception of feed wires. The switch 22 is operated by a pull cord or chain 25, which 20 passes between the base 10 and casing 11, and through a groove 26 formed in the former.

To prevent contact of the feed wires with the casing, the upper portion of the latter is lined with a suitable lining 27 of insulation, said lining being formed with a central opening 28, for the passage of the feed wires. 30

Disposed in the casing 10 and directly 35 above the opening 28 in the lining 27, is an internally threaded bushing 29, adapted for connection with a pipe or conduit to afford passage for the feed wires. This bushing 29 has a multi-sided flanged portion 30 formed thereon, and is grooved to receive a washer 31, the latter serving to lock the bushing 29 against relative longitudinal movement by positioning of the upper peripheral edge thereof against the inner surface of the upper portion of the casing 11 as shown at 31^a in Fig. 1. A flanged portion 32 is formed integral with the casing, and is clamped between the washer 31 and the bushing 29. The casing 40 10 thereby snugly embraces the bushing, which is positively locked against relative rotation with respect to said casing.

As before indicated, it is desirous that the binding terminals be easily accessible 55 whereby the feed wires may be replaced in case they become loosened or broken. With this in mind reference may be had to Fig. 5 wherein the insulating base 10 is shown as provided with recesses at 33 and 34, in which the terminals 23 and 24 respectively, are positioned, while the casing 11 is correspondingly recessed at 35 and 36.

It is not desired that the binding terminals be exposed as shown in Fig. 5, so a 60 sleeve 37 is provided, which is telescopic-

cally mounted on said casing 11. Formed integral with said sleeve 37, and extending vertically downwardly therewithin, is a finger 38 which has shoulder portions 39 formed thereon. The lower edge of said 70 sleeve is flanged at 40 to support an annular insulating lining 41.

Should it be desired to replace a loosened or broken feed wire at the binding terminals, it is only necessary to remove the 75 sleeve 37 and the lining 41, said lining being removed with said sleeve. This action will expose the parts as shown in Fig. 5.

When replacing the sleeve 37, the finger 38 will engage an aperture 42 (Fig. 5) in 80 the casings, and also engage an aperture 43 in the insulating lining 27, (Fig. 7) both of said apertures being positioned directly above one of the longitudinal recesses 17 of the bayonet joint. The finger 85 38 will therefore, after entering the apertures 42 and 43, engage one of said longitudinal recesses 17 to positively hold the lugs 16 in the transverse recesses 18, and hold the base and casing in locked relation. 90 When the finger 38 is in engagement with the longitudinal recess 17, the flange portion 40 of the sleeve 37 will rest upon a shoulder 44 formed between the casing 11 and husk 12 formed integral therewith. 95 The shoulder 39 on the finger 38 will also serve as a support for said sleeve on the casing 11.

It is evident from the construction as outlined above, that the operator has quick 100 and easy access to the binding terminals, and when the sleeve 37 is in position it will serve both to cover the openings 24 to the binding terminals and positively hold the base and casing parts in locked relation. 105

While I have shown and described but one embodiment of my invention, it is apparent that many modifications therein may occur to those skilled in the art, and I desire therefore, that my invention be 110 limited only by the showing of the prior art or by the scope of the appended claims.

Having thus described my invention, what I claim as new and desire to secure by Letters Patent is:

1. An electrical receptacle comprising a base having binding terminals mounted thereon and provided with locking slots, and casing provided with means cooperating with said slots associated with said base and having openings therein affording access to said binding terminals, and a sleeve for closing said openings, said sleeve having means formed integral therewith for positively holding said base and casing in 120 locked relation.

2. An electrical receptacle comprising a base having binding terminals mounted thereon and provided with locking slots, and casing provided with means cooperating 125

with said slots associated with said base and having openings therein affording access to said binding terminals, and a sleeve telescopically received by said casing having a finger formed integral therewith, said sleeve serving to close said openings and said finger positively locking the base and casing in locked relation.

3. An electrical receptacle comprising a base having binding terminals mounted thereon and provided with locking slots, and casing provided with means cooperating with said slots associated with said base and having openings therein affording access to said binding terminals, a sleeve for closing said openings and having a finger formed integral therewith for positively locking said base and casing, and an insulating lining carried by the sleeve and movable therewith.

4. An electrical receptacle comprising a base having binding terminals mounted thereon and provided with locking slots, and casing provided with means cooperating with said slots associated with said base and having openings therein affording access to said binding terminals, a sleeve for closing said openings having a finger thereupon, said casing having an opening adapted to receive said finger and said base member having a recess registering with said last named opening whereby said finger operates to positively lock said base and casing when said sleeve closes said binding terminal openings.

5. An electrical receptacle comprising a base having binding terminals mounted thereon and provided with locking slots, a casing having openings therein affording access to said binding terminals, and provided with means for co-operating with said slots and having an additional opening adapted to register with the one of said locking joints in said base, and means comprising a telescopically received sleeve for closing said terminal openings and a finger adapted to pass through said last named casing opening and to engage said one of said locking joints to positively lock the base and casing.

6. An electrical receptacle construction comprising an insulating base having binding terminals and receptacle contacts mounted thereon, a casing having openings therein affording access to said terminals, means for detachably securing said base and the parts supported thereby in said casing, and means for preventing detachment of said base and

parts supported thereby, and for closing the openings in said casing, comprising a sleeve surrounding said casing, and provided with a locking finger, for holding said base against rotation, said casing being provided with an annular shoulder, for supporting said sleeve.

7. An electrical receptacle construction comprising an insulating base, wiring terminals and receptacle contacts mounted thereon, a casing having openings therein affording access to said terminals, and means whereby said base and parts supported thereby may be detachably secured in said position by a movement including a movement of rotation, and means for closing the openings in said casing, and preventing rotation of said insulating base, comprising a sleeve surrounding said casing, said casing being provided with two shoulder portions, one engaging the lower portion of the sleeve, and one shoulder portion having an opening therein, and a member carried by said sleeve extending through said last opening for preventing rotation of said insulating base and the parts supported thereby.

8. An electrical receptacle construction comprising a sub-assembly including (1) an insulating base; (2) a threaded shell contact mounted on said base; and (3) a wiring terminal mounted on said insulating base; a casing enclosing said sub-assembly, and having an opening therein affording access to said wiring terminal, said sub-assembly being provided with a bayonet joint connection for holding it in position in said casing; and a sleeve surrounding said casing for closing said opening, said sleeve being provided with means for preventing disconnection of said bayonet joint.

9. An electrical receptacle construction comprising a sub-assembly including (1) an insulating base; (2) a threaded shell contact mounted on said base; and (3) a wiring terminal mounted on said insulating base; a casing enclosing said sub-assembly; said sub-assembly being provided with means whereby it may be detachably secured in position in said casing by movement including a movement of rotation, and a sleeve for surrounding said casing, and closing said opening, said sleeve being provided with means to hold said sub-assembly against rotation to prevent it from becoming disconnected.

In witness whereof, I have hereunto subscribed my name.

REUBEN B. BENJAMIN.

Certificate of Correction.

It is hereby certified that in Letters Patent No. 1,548,577, granted August 4, 1925, upon the application of Reuben B. Benjamin, of Chicago, Illinois, for an improvement in "Electrical Receptacles," an error appears in the printed specification requiring correction as follows: Page 3, lines 43 and 49, claim 5, for the word "joints" read *slots*; and that the said Letters Patent should be read with this correction therein that the same may conform to the record of the case in the Patent Office.

Signed and sealed this 22d day of September, A. D. 1925.

[SEAL.]

KARL FENNING,
Acting Commissioner of Patents.
